UNITED STATES PATENT OFFICE

WILLIAM G. KIRCHHOFF, OF CINCINNATI, OHIO, ASSIGNOR TO THE J. H. DAY COMPANY, OF CINCINNATI, OHIO, A CORPORATION OF OHIO

SHEETER AND CURLING ROLL ADJUSTMENT DEVICE

Application filed May 14, 1931. Serial No. 537,255.

This invention relates to a sheeter and curling roll adjustment device for dough working machinery.

An object of the invention is to provide a combination of sheeter and curling device provided with a means for insuring discharge of curled or shaped parcels of dough in accurately timed succession.

A more specific object is to provide a sheeter and curler with means for varying the relative speeds of operation of those elements, whereby is secured a very accurately timed discharging of loaves from the machine.

Another object of the invention is to provide a sheeter and curling device with means for insuring discharge of successive loaves in a substantially horizontal or other desired plane.

These and other objects are attained by the means described herein and disclosed in the accompanying drawings, in which:

Fig. 1 is a fragmental side elevational view of the sheeter and curler of the invention, showing it in cooperative relationship with a conventional dough molder drum.

Fig. 2 is a diagrammatical view showing the manner in which shaped loaves are released from the curling means.

Fig. 3 is an elevational view taken on line 3—3 of Fig. 1.

Fig. 4 is a cross-sectional view taken on line 4—4 of Fig. 3.

Fig. 5 is a fragmental cross-sectional view showing in detail the means for insuring discharge of the successive loaves in a substantially horizontal or other given position.

It has been customary, heretofore, to associate a curling mechanism with a dough sheeter in substantially the relative positions illustrated in the drawings, the sheeter mechanism and the curling device being operated from a common power source. The power transmission means heretofore was a direct drive not providing for adjustment of the speed of the curling device relative to the speed of the sheeting mechanism. In other words, by speeding up the machine to effect an increase in the rate of loaf discharge, the speeds of operation of the sheeting means

and the curling device heretofore were increased simultaneously and without changing the relative speeds of the sheeter and curler devices. Under the above conditions, the curled sheets or parcels were found to leave the curler in an irregular succession, especially at the higher speeds of operation, at which speeds the curled rolls or parcels would at times remain under the influence of the curler after completion of the curling operation. It has been discovered, however, that a more accurately timed discharge of loaves may be obtained by varying the speed of rotation of the curling device relative to the speed of operation of the sheeter mechanism, in those instances wherein a rapid succession or a change in the rate of discharged loaves is desired. Accordingly, a suitable change speed device, one form of which is illustrated at the right hand side of Fig. 3, is associated with the sheeter and curler for the purpose of obviating the foregoing difficulties encountered in variable speed machines of the character set forth herein. Cooperatively associated with the curling device is a loaf positioning means, shown in detail in Fig. 5, whereby successive loaves leaving the curling device are precluded from entering a loaf molder in a cocked or crooked condition. A detailed description of the improved machine follows.

The invention disclosed herein is applicable to any dough working machine employing a curling roller, or other roller, performing the function of a curling roller. Reference is made to the patent of William G. Kirchhoff Number 1,740,024 wherein is disclosed one type of dough molder to which the device of the present invention may be conveniently applied. Reference is made also to the patent of William G. Kirchhoff 1,828,049 which shows in detail an adjustable guide means associated with a curling roller in substantially the manner disclosed herein.

In the drawings, the pairs of cooperating driven rollers 6 and 7, and 8 and 9 correspond to pairs of driven rollers 62 and 63, and 64 and 65, respectively, of the above referred to Patent Number 1,740,024. Measured lumps of dough are successively inserted between

100

the pair of rollers 8 and 9 where they are flattened and worked into sheet form. The dough in this form passes between the second pair of rollers 6 and 7 wherein the flattening operation is completed. The sheet of dough thus formed is projected downwardly until its free end 11 (Fig. 2) strikes the serrated curling roller 10, which is driven in counterclockwise direction as indicated by the arrow 10 in Fig. 2. The rotating curling roller thereupon carries the end 11 toward a pilot roller 12, driven in a counterclockwise direction as indicated by the arrow 13. The pilot roller thereupon contacts the end 11 and turns said end upon itself. Continued rotation of the curling and pilot rollers results in a spiral winding of the sheet about a central longitudinal axis of rotation. The roll or loaf thus formed is indicated at 110 in Fig. 2.

Attention is directed to the fact that although the center of gravity of the cylindrical loaf 110 may be disposed considerably to the right of a vertical line 14 passing through the central axis of the curling roller 10, the counterclockwise rotation of the curling roller will serve to prevent gravitation of the loaf down the face of the curling roller. This tendency of the formed loaf to remain upon the curling roller after completion of the winding operation, is particularly noticeable when the speed of operation of the machine is increased. By decreasing the speed of the curling mechanism while the other parts of the machine are operating at comparatively high speed, the difficulty above set forth is overcome. Accordingly, the curling mechanism is provided with a change speed drive, which is indicated generally by the character 15, whereby the speed of the curling mechanism may be decreased although the sheeting device is in operation at an increased speed.

Although there is disclosed herein a specific type of change speed device cooperating with the curling mechanism for the purpose above explained, it is to be understood that the invention is not to be limited to any specific mechanism for varying the speed of operation of the curling device relative to that of the sheeting device.

Before proceeding with a detailed description of the change speed mechanism shown herein, an explanation will be given as to the manner in which the various rolls and shafts of the device may be driven by means of the motor 16. The motor preferably is provided with a sprocket 17 over which passes a chain 18 for driving a sprocket 19 on the main shaft 20 of the machine. The direction of rotation of the main shaft is indicated by the arrow 21. The main shaft has fixed thereon a sprocket 22 which, by means of a chain 23 rotates the sprocket 27 of the sheeter roll 6 in a clockwise direction of rotation, as indicated. The sprocket 27 is fixed on the shaft 65 of the sheeter roll 6. The chain 23 drives an

idler consisting of sprockets 24 and 25, each of which is fixed on the hub 26, which hub may rotate freely on a suitable bearing 28. The rear upper sheeter roll 8 may be rotated with the roll 6 by means of the chain 29 which may engage the sprockets 30 and 31 fixed on the shafts of rolls 6 and 8 respectively. The lower and upper front sheeter rolls 7 and 9, may be rotated by means of the chains 32 and 33 which transmit rotary motion of the sprocket 24 to the sprockets 34, 35 and 36 which, as shown, are fixed on the shafts of sheeter rolls 7 and 9. The sprocket indicated at 37 is an idler which serves as a chain tension adjustment. The sheeter rolls are adjustable relatively by means of the hand wheels 38.

The driven shaft 39 to which the sheeter roll 6 is fixed, may be extended as shown at 40 to provide a mounting for each of the gears 41, 42 and 43 which are arranged on the shaft in stepped or cone fashion. Each of said gears has a bore provided with a narrow keyway 44 which may register with a cooperative longitudinal slot 45 provided in the shaft extension 40. The gears are freely rotatable on the shaft extension, but may be locked thereto by means of the sliding change gear member or key 46 which rides in the slot 45 and may be shifted longitudinally therein for disposition of its extending abutment or projection 47 in any one of the gear key-ways 44. The projection 47 is yieldingly held in an extended position by means of the spring 48 which contacts the bottom wall of the groove or slot 45. A suitable handle 49 is provided for manual shifting of the sliding key 46 which may be referred to as a clutch member. The member 46 rests on a fulcrum 50.

Between the gears 41, 42, and 43, are placed the circular washers 51 and 52 which break the continuity of the gear key-ways and serve to provide obstructions between the gears for depressing the wedge-shaped head or projection 47 of the clutch member. By referring to Fig. 3, it should be obvious that an inward shifting of the clutch member 46 will cause the wedge-shaped head or projection 47 to strike the circular washer 52 and to be guided thereby downwardly and into the slot 45, against the resistance of the spring 48, thereby terminating the driving connection between the shaft 39 and gear 43. After leaving the washer 52 the head or projection 47 may engage the key-way of gear 42 and thereby establish a driving connection between the gear 42 and the shaft 39. In a similar manner, the gear 41 may be placed in driving relation with the shaft, by further shifting the member 46 to the left. The circular washers are readily seen to provide a means for automatically terminating the drive connection upon each shifting movement of the clutch member 46. The gears on

shaft 40 may be maintained in abutting relationship by means of the collar 53 which is fixed to said shaft.

The gears 41, 42, 43 are in constant mesh with the gears 54, 55, 56, which may be keyed or otherwise secured to the pilot roller shaft 57 as illustrated, or to the shaft 58 of the curling roll 10. In the device illustrated herein, the curling roll shaft 58 is driven from the 10 variable speed shaft 57 by means of the chain and sprocket connection 59. The connection 59, of course, could be replaced by suitable gearing or other power transmission means. If desired, the curling roll shaft 58 could be 15 made to carry the gears 54, 55, 56, and the shaft 57 could be driven therefrom.

It is evident from the foregoing, that the change gear device indicated generally at 15 provides one form of means whereby the 20 speed of the curling and pilot rollers may be varied relative the speed of operation of the sheeter rolls. When the machine is running at a comparatively high rate of speed, the curling mechanism thereby may be adjusted 25 independently to run at a speed conducive to proper discharging of the curled sheets or parcels in accurately timed succession. As stated before, the improved construction set forth herein eliminates the tendency 30 of curled sheets or parcels to remain atop the curling roll after completion of the curling operation.

The change speed mechanism may be used in conjunction with, or without, the adjustable guide 60 which corresponds to the guide 15 illustrated and fully described in the copending Kirchhoff Patent Number 1,828,049. The use of the variable speed curler mechanism with the adjustable guide device 60 in 40 a machine of the character under consideration, renders the guide device more efficient in its operation, but it is to be understood that the speed range of the change gear device may be such as to render unnecessary the 45 use of a guide such as is illustrated at 60.

Briefly, the adjustable guide means comprises the curved plate 60 which extends part way around the curling roll 10, as indicated in Fig. 2. The plate is suitably mounted 50 at its ends, on bearings 61 provided on the dough molder frame or on the curling roller shaft. By means of a longitudinally adjustable rod 62 having a pivotal connection 55 with the lever 63 which is fixed relative the adjustable curved plate 60, the plate may be adjusted so as to vary the distance between its uppermost edge 63 and the axis of the pilot roller 12. Reference is made to the copending Kirchhoff patent hereinbefore referred to, for the details of construction of 65 the adjustable curved guide plate 60, which corresponds to the member 15 in the copending application. It is sufficient, for the purposes of the instant application, that there

be provided an adjustable curling roll guide 60 of the general character above described.

Adjacent the front portion of the curling-roller or its adjustable guide 60 is disposed a transverse substantially flat inclined plate or support 64, which may be fixed to the frame of the machine as indicated at 65. The shaped loaves, as they leave the curling roll, may roll down said plate. At the lower edge 66 of the plate is hinged, as at 67, a loaf straightener or righting means, which may be in the form of a substantially flat inclined plate 68 disposed at substantially the same inclination as the stationary plate 64. By means of a spring 69 or the like, the hinged or movable member 68 is yieldingly maintained in the outwardly extended position illustrated, the spring being just strong or resili- 75 ent enough to yield and permit the plate to move downwardly to a substantially vertical 80 position when the hinged plate is struck by a loaf released from the curling mechanism. The yieldingly movable plate thereby has the effect of leveling or straightening any loaf 85 that may leave the curler with one of its ends 90 in advance of the other. By means of the ar- 95 rangement just described, it is rendered a certainty that each and every loaf leaving the curling mechanism will be received by the primary molder 70 in a perfectly horizontal 100 or other given position. The molder com- 105 prises the flanged drum 71 having associated therewith a curved pressure board 72 as illus- 110 trated and described in the patent of Kirch- 115 hoff No. 1,740,024. The movable loaf right- 120 ing member 68 (Fig. 1) is disposed adjacent the top edge 72 of the pressure board. It is to be understood that the loaf righting mem- 125 ber may have yielding movement other than a hinge movement, it being possible also to mount said member for oscillatory or rotary movement to the depressed position. It is to be understood that various other modifica- 130 tions and changes in structural details of the device may be made, within the scope of the appended claims, without departing from the spirit of the invention.

What is claimed is:

1. In a device for developing masses of plastic material into sheets and rolling the sheets to cylindrical shape, the combination of a power operated sheet forming means, a curling mechanism and a drive means therefor the curling mechanism being located so as to receive the sheeted material from the sheet forming means for development there- 115 of into cylindrical-shaped loaves, and means for varying the speed of operation of the curling mechanism relative to that of the sheet forming means.

2. In a device for developing masses of plastic material into sheets and rolling the sheets to cylindrical shape, the combination of a power operated sheet forming means, a curling mechanism and a drive means there- 120 125 130

for the curling mechanism being located so as to receive the sheeted material from the sheet forming means for development thereof into cylindrical shaped loaves, means for varying the speed of operation of the curling mechanism relative to that of the sheet forming means, and means associated with the curling mechanism for effecting release of the cylindrical shaped loaves from the curling mechanism upon completion of the loaf forming operation.

3. In a device for developing masses of plastic material into sheets and rolling the sheets to cylindrical shape, the combination of a power operated sheet forming means, a curling mechanism and a drive means therefor the curling mechanism being located so as to receive the sheeted material from the sheet forming means for development thereof into cylindrical shaped loaves, means for varying the speed of operation of the curling mechanism relative to that of the sheet forming means, and means associated with the curling mechanism for lifting the shaped loaves from contact with the curling mechanism upon completion of the loaf forming operation.

4. In a device for developing masses of plastic material into sheets and rolling the sheets to cylindrical shape, the combination of a power operated sheet forming means, a curling mechanism and a drive means therefor the curling mechanism being located so as to receive the sheeted material from the sheet forming means for development thereof into cylindrical shaped loaves, means for varying the speed of operation of the curling mechanism relative to that of the sheet forming means, means associated with the curling mechanism for effecting release of the cylindrical shaped loaves from the curling mechanism upon completion of the loaf forming operation, and a loaf righting means associated with the curling mechanism for effecting discharge of loaves in a uniformly level condition.

5. In combination a dough molder adapted to receive and roll initially formed loaves, a sheet forming means and a curling mechanism associated therewith for receiving the sheeted dough and developing it into cylindrical shaped loaves, the sheet forming means and the curling mechanism being operated by a common power means, change speed means for varying the speed of the curling mechanism relative that of the sheet forming means, and a loaf straightener adapted to direct successive initially shaped loaves into the dough molder in a uniformly level condition.

6. In a device of the class described the combination of a pair of spaced driven rolls adapted to receive lumps of plastic and to form them into sheets, a driven curling roll and a driven pilot roll rotating in a common

direction of rotation and located below the sheet forming rolls whereby to receive the sheets as they are formed and to roll them into cylindrical loaves suitable for reception in a loaf molder, a loaf righting means comprising a loaf intercepting member for precluding discharge of the cylindrical loaves from the curling roll with one end of the loaf in advance of its other end and means for mounting the loaf intercepting member so that it is contacted by the formed cylindrical loaf before said loaf is influenced by the loaf molder.

7. In a device of the class described the combination of a pair of spaced driven rolls adapted to receive lumps of plastic and to form them into sheets, a driven curling roll and a driven pilot roll rotating in a common direction of rotation and located below the sheet forming rolls whereby to receive and form them into cylindrical loaves, and a speed adjusting means for varying the speeds of operation of the sheet forming rolls and the curling roll, relatively.

8. In a device of the class described the combination of a pair of spaced driven rolls adapted to receive lumps of plastic and to form them into sheets, a driven curling roll and a driven pilot roll rotating in a common direction of rotation and located below the sheet forming rolls whereby to receive the sheets as they are formed and to roll them into cylindrical loaves, a speed adjusting means for varying the speeds of operation of the sheet forming rolls and the curling roll, relatively, a normally stationary guide member disposed in close proximity with the curling roll, and movable supporting means for moving the guide member concentrically about the curling roller.

9. The combination with means for coiling sheets of material into substantially cylindrical rolls, said means comprising a curling roller arranged to exert a lifting force upon the said cylindrical rolls while in the process of formation, of independently adjustable rotatably supported means movable to positions beneath the formed roll for releasing said roll from the lifting influence of the curling roller, thereby permitting gravitation of the formed roll from its position above the curling roller, and a righting means disposed adjacent to the roll releasing means and comprising an intercepting member adapted to be struck by the released roll prior to subjection of said roll to another machine, whereby to preclude discharge of the roll to said other machine with one of its ends in advance of the other.

10. The combination with means for coiling sheets of material into substantially cylindrical rolls, said means comprising a curling roller arranged to exert a lifting force upon the said cylindrical rolls while in the process of formation, of independently ad-

justable rotatably supported means movable to positions beneath the formed roll for releasing said roll from the lifting influence of the curling roller, thereby permitting gravitation of the formed roll from its position above the curling roller, means for feeding sheet material to the coiling means, and means for varying the speeds of operation of the sheet feeding means and the coiling means, relatively.

10 11. In combination a power actuated device for feeding plastic masses in sheet form, a driven rotatable curling roller positioned to receive an end of the sheet, a driven pilot roller having its axis above and to one side of a vertical diameter of the curling roller and cooperating with the curling roller to effect coiling of the fed sheet atop the curling roller, and a change speed means for varying the speeds of operation of the feeding means and the curling roller relatively.

In testimony whereof I have hereunto subscribed my name this 7th day of May, 1931.

WILLIAM G. KIRCHHOFF.
